UNITED STATES PATENT OFFICE.

ALFRED W. FRENCH, OF PIQUA, OHIO.

OIL-EXPRESSING APPARATUS.

1,158,797.

Specification of Letters Patent.

Patented Nov. 2, 1915.

Application filed July 22, 1914. Serial No. 852,400.

To all whom it may concern:

Be it known that I, ALFRED W. FRENCH, a citizen of the United States, residing at Piqua, in the county of Miami and State of Ohio, have invented a new and useful Improvement in Oil-Expressing Apparatus, of which the following is a specification.

This invention relates more particularly to oil expressing apparatus of that kind in which the presses used are of the cage type in which the meal or oil bearing material is introduced in successive layers with intervening press plates and cloths into the open top of the press box or cage, and is compressed between a removable pressure block or cover at the upper end of the cage and a ram which moves upwardly in the cage.

The object of the invention is to provide a practical and efficient apparatus of comparatively simple and inexpensive construction, whereby a plurality of presses, arranged around a meal cooker, can be charged directly from the cooker and operated one after another with the maximum speed and minimum amount of labor, thereby insuring a large output at a small operating expense.

In the apparatus hereinafter described in detail, a plurality of presses of the open-top cage type are arranged in a circular series around a meal cooker which is provided with a press charging device which is movable to place it in position to charge the presses one after another, and which is adapted to be operated to carry to the press charges of material received from the cooker. Each press has a ram which is movable vertically in the press box, and a vertically movable pressure block or cover against which the material is pressed by the upward movement of the ram. This pressure block is raised away from the press box when charging the press, and the ram, which, at the commencement of the charging operation is in the upper portion of the press box, is gradually lowered to make room for the successive charges. When the charging device has deposited a charge of meal into the upper end of the press box, an operative places a press cloth on this charge, then a press plate on this cloth, and another press cloth on the press plate, after which the charging device is again operated

to deliver another charge of meal into the press box, this operation being repeated until the press box is filled. When the press box has been filled with the desired number of charges, the pressure block is lowered to the upper end of the press box and a spacing block or abutment is moved into place between the pressure block and the stationary head of the press to hold the pressure block rigid, and the ram is sent up to express the oil from the material. After the oil has been expressed the abutment is moved from its position over the pressure block and the latter is raised. The ram is then caused to move upwardly and the operative removes the cakes successively as they are pushed out of the upper end of the press box and places the press plates and cloths in a convenient position for use again. After one press has been charged the charging device is moved into operative relation to the next press, which is charged and operated to express the oil in a similar manner. The charging device is preferably reciprocated radially to deliver the charges to the presses by hydraulic actuating means, and the pressure block is also similarly actuated.

In the accompanying drawings: Figure 1 is a diagrammatic plan view, on a reduced scale, indicating the relative arrangement of the cooker and the presses. Fig. 2 is an elevation, partly in section, of the cooker and one of the presses. Fig. 3 is a horizontal section of the lower portion of the meal cooker showing the location of the discharge openings thereof. Fig. 4 is a plan view of the press box. Fig. 5 is a fragmentary sectional elevation, on an enlarged scale, showing one of the presses and the lower portion of the meal cooker and charging device. Fig. 6 is an enlarged sectional elevation of the swivel connection for the pipes of the hydraulic operating mechanism of the charging device. Fig. 7 is a sectional elevation, on an enlarged scale, showing the charging device and the lower portion of the meal cooker. Fig. 8 is a sectional elevation of one of the presses showing the position of the parts when preliminarily compressing the material to take up the slack. Fig. 9 is a fragmentary similar view, showing the abutment in position for holding the

pressure block rigid for expressing the oil. Fig. 10 is a sectional plan view in line 10—10, Fig. 9.

5 A represents a meal cooker around which are arranged, in fixed positions in the arc of a circle concentric with the cooker, a series of presses 1, 2, 3, 4, 5, 6, of which there may be any desired number. Except as herein-after described, the cooker may be of any 10 suitable construction.

15 B represents the charging device for carrying the meal in measured charges from the cooker to the presses. This charging device is mounted to swing in an arc concentric with the line of presses 1—6 to place it in operative position radially in line with any one of the presses, and consists of a charge box b adapted to receive a charge of meal from the cooker, and means for reciprocating the same from the position in which it receives the meal from the cooker to a position to drop the charge of meal into the open end of the box or cage of the press. The charging device could be adapted to 20 thus deliver the charges of meal to the several presses in various ways, as for instance by rotatably mounting the meal cooker to turn as a whole with the charging device, or by providing the cooker with a lower kettle or bottom portion adapted to thus rotate with the charging device, in order that the charging device can reciprocate between the discharge opening of the cooker to one or another of the presses. Preferably, however, the cooker, as shown in the drawings, 25 is stationary and has a series of bottom discharge openings a'—a⁶, Fig. 3, corresponding in number with the presses 1—6 and arranged radially in line therewith, and the 30 charging device B is rotatably mounted so that it can be swung horizontally beneath the cooker to place the charge box b into position to receive the material from one or another of the several discharge openings 35 a'—a⁶. Each of these discharge openings is provided with a slide door a⁷ or other suitable closure, all of which remain closed except the one for the opening beneath which the charging device is positioned.

40 C represents a supporting frame for the charging device. This frame, as shown, has a swivel connection c of any suitable construction with the central portion of the bottom of the cooker, and is provided at its outer end with an upwardly extending portion c' having laterally projecting lugs or flanges c² which bear and are adapted to slide on inner and outer flanged circular rails c³ and c⁴ secured to the bottom of the 45 meal cooker. The upwardly extending portion c' of the frame is hollow and forms an open-ended discharge spout for the meal adapted to register separately with the discharge openings a'—a⁶ in the bottom of the 50 cooker. This discharge spout c' is prefer-

ably of rectangular shape in cross-section, with its upper end corresponding in dimensions with the discharge openings, and flares downwardly to insure the free discharge of the meal.

55 The charge box b may be of usual form, consisting of an open-ended rectangular box, preferably flaring downwardly, which is adapted to register with the lower end of the discharge spout c'. The charge box 60 rests and is adapted to slide on an underlying horizontal floor or portion d of the frame C and is provided with the usual plate or apron d' extending horizontally from the upper end of the box for closing the 65 discharge spout when the box is moved outwardly to deliver a charge to one of the presses.

70 The charge box is reciprocated preferably by hydraulic operating mechanism similar 75 to that disclosed in Patent No. 1,059,986, granted to me April 29, 1913. Briefly stated, this mechanism is constructed and operates as follows: E represents a piston rod which is secured to the charge box b 80 and is provided with a piston arranged to reciprocate in a horizontal cylinder e which is supported on the frame C radially with reference to the cooker. Operating liquid under pressure is admitted to the outer end 85 of the cylinder by a pipe e' and to the inner end of the cylinder by a pipe e². These pipes lead from the casing of a valve e³ for controlling the passage of the operating liquid to and from the ends of the cylinder 90 e for reciprocating the piston and the charge box. Liquid supply and discharge pipes e⁴ and e⁵ lead to the casing of the controlling valve e³. The valve e³ admits the operating liquid at all times from the supply pipe to 95 the outer end of the cylinder through the pipe e'. When it is desired to move the charge box outwardly to deliver a charge to one of the presses the valve e³ is moved by a lever e⁶, or other suitable actuating device, 100 to a position to connect the supply pipe e' with the pipe e² leading to the inner end of the cylinder, and the pressure of the liquid on the inner end of the piston moves the piston outwardly against the opposing pressure 105 on the opposite end of the piston which is of less area than the inner end of the piston. The valve is held in this position by a suitable latch device e⁷, Fig. 7, until the charge box reaches the end of its travel, 110 when a trip device e⁸ on the apron d' trips the latch e⁷ and the valve is returned by a spring e⁹. When the valve is thus returned 115 it connects the pipe e² leading from the inner end of the cylinder with the discharge pipe e⁵, and the pressure of the liquid on the outer end of the piston moves the piston and the charge box connected thereto inwardly. 120 As no claim is made herein to this hydraulic 125 operating mechanism for the charge box the 130

above description is believed to be adequate. The mechanism is more fully shown and described in said patent. Mechanism of any other suitable construction for reciprocating the charge box could be employed.

In order to enable the charging device to be swung horizontally into operative relation to one or another of the discharge openings of the cooker and be reciprocated in the different positions, the supply and discharge pipes e^4 e^5 for the hydraulic reciprocating mechanism are provided with a swivel joint or connection F, which is located co-axially with respect to the charging device. This swivel connection may be of any suitable construction. As shown in Fig. 6, it comprises a casing f provided with inner and outer passages or chambers f^1 and f^2 respectively. A stationary supply pipe f^3 connects with the inner chamber f^1 and a stationary discharge pipe f^4 lead from the outer chamber f^2 . The supply pipe e^4 leading to the controlling valve e^3 is connected to the upper end of the casing f in communication with the inner chamber f^1 thereof, by a screw cap f^5 in which the pipe is adapted to turn or swivel. The cap f^5 is provided with a packing gland f^6 to prevent leakage of the liquid around the pipe e^4 . Surrounding and adapted to turn on the casing f is a swivel sleeve f^7 provided at opposite ends with packing glands or stuffing boxes f^8 f^9 to prevent leakage through the joint between the sleeve and the casing. The discharge pipe e^5 leading from the controlling valve e^3 connects with the sleeve which is chambered interiorly and connects with the outer chamber f^2 of the casing through one or more holes f^{10} in the wall of the casing. A swivel joint or connection of simple and practical construction is thus provided between both the supply and discharge pipes e^4 and e^5 which swing with the charging device, and the stationary supply and discharge pipes.

The press comprises a vertical cylinder G, a ram or plunger g arranged to move vertically therein, a press head H connected by bolts h to the cylinder, and an open-ended press cage or box I which is secured on the cylinder between the same and the press head. These parts may be of any usual or suitable construction. The press head H is formed with or has secured thereon in any suitable manner an upright cylinder h' in which is arranged to reciprocate vertically a piston or plunger h^2 which extends through the lower end of the cylinder and carries a pressure block or cover K adapted to enter and close the upper end of the press box I. This pressure block K is adapted to be lowered into and raised out of the press box by liquid under pressure admitted to the cylinder h' by means of any suitable connections not shown.

The press cage or box I may be of any suitable construction, but, as shown in Fig. 4, it preferably consists of an outer steel cylinder or ring i and four segmental blocks i' therein forming a rectangular pressing chamber. In order to afford the necessary drainage, these blocks may be grooved, as shown at i^2 , and covered with perforated plates or mats i^3 , or narrow vertical strips, shown at i^4 , may be arranged vertically close together against the inner faces of the blocks i' with intervening V-shaped drain passages, see Fig. 4.

L represents a spacing block or abutment for holding the pressure block K rigid when pressing the material in the press box. This abutment, as shown, consists of a strong block or casting which is pivoted at one end to swing horizontally on a sleeve l surrounding one of the bolts h which connect the press head and cylinder. The outer or free end of the abutment is slotted vertically at l' to permit it to be swung into a position between the pressure block and the press head, the slotted portion straddling the plunger h^2 which supports the pressure block. When the abutment is in place between the pressure block and press head it transmits the pressure on the pressure block to the stationary press head and holds the pressure block rigid. In order to raise the pressure block to open the upper end of the press box, the abutment is first swung out of the way from over the pressure block.

In the operation of the apparatus, after the press box of a press has been filled to the top with loose deposits of meal separated by the press plates and cloths in the manner explained and before operating the ram to express the oil, the pressure block K is preferably lowered into the end of the press box by admitting liquid to the cylinder h' , the ram g is caused to move upwardly in the press box to pack the material and take up the slack without expressing the oil. In this way room is made for several more cakes. The pressure block is then raised, the ram started down again and the charging device operated to deposit the additional charges necessary to fill the space remaining in the press box. The pressure block K is then lowered again into the upper end of the press box, the abutment L is swung into place between the pressure block and the press head H to hold the block rigid, and the ram is sent up again to express the oil. In order to remove the abutment to permit the pressure block to be raised for discharging the pressed cakes from the upper end of the press box, it is first necessary to relieve the pressure of the pressure block on the abutment. This is done by admitting liquid pressure to the cylinder h' to force the piston h^2 and pressure block K down sufficiently to admit of the abutment being read-

ily swung out of position over the pressure head. The pressure block K can then be raised and the press discharged as before explained. The press cylinders can be arranged below the floor line so as to locate the tops of the press boxes at a height convenient for an operative standing on the floor, or if desired the presses can be located above the floor and a platform provided at 10 a suitable height for the operative to stand upon.

I claim as my invention:

1. The combination of a cooker, a plurality of presses arranged in relatively fixed 15 positions around said cooker, said cooker having a discharge spout which is movable to place it in operative relation to any one of said presses, a press charging device which is movable with said spout and is 20 adapted to receive material therefrom in the several positions of the spout, said charging device being also movable from said spout to the adjacent press for charging the press.

2. The combination of a cooker, a plurality of presses arranged in relatively fixed 25 positions around said cooker, a charging device for the presses which is mounted to swing to a position radially in line with each of said presses, said charging device being 30 also movable radially to carry a charge of material received from said cooker to the press which is radially in line with the charging device.

3. The combination of a cooker, a plurality of presses arranged in relatively fixed 35 positions around said cooker, a charging device for the presses which is arranged to receive material from said cooker and is mounted to swing about an axis at the center 40 of said cooker to place it in operative relation to any one of said presses, said charging device being also mounted to reciprocate radially to carry the charge of material from the cooker to the adjacent press.

4. The combination of a cooker, a plurality of presses arranged in relatively fixed 45 positions around said cooker, a charging device for the presses which is arranged to receive material from said cooker and is mounted to move horizontally from an operative relation to one of said presses to an operative relation to another of said presses, said charging device being also mounted to reciprocate radially relative to said cooker 50 from a position to receive material from the cooker to a position over the press which is in operative relation to the charging device.

5. The combination of a cooker, a plurality of presses arranged in relatively fixed 60 positions around said cooker, a charging device for the presses which is arranged to receive material from said cooker and is movable from an operative relation to one 65 of said presses to an operative relation to

another of said presses, and actuating mechanism for moving said charging device from a position to receive material from the cooker to a position over the adjacent press, said mechanism being operative in the several different operative positions of said charging device.

6. The combination of a cooker, a plurality of presses arranged in relatively fixed 70 positions around said cooker, a charging device for the presses which is arranged to receive material from said cooker and is movable from an operative relation to one of said presses to an operative relation to another of said presses, said charging device 75 being also movable to carry a charge of material from the cooker to the press, and a single mechanism for moving said charging device in the different operative positions thereof to carry the material from the cooker 80 to the press.

7. The combination of a cooker having a plurality of bottom discharge openings, a plurality of presses arranged around said cooker radially in line with said discharge 90 openings, a charging device for the presses which is movable to place it in position to receive material from any one of said discharge openings, and which is also mounted to reciprocate radially to carry material 95 from the discharge opening to the adjacent press.

8. The combination of a cooker having a plurality of bottom discharge openings, a plurality of presses arranged around said 100 cooker radially in line with said discharge openings, a discharge spout which is movable to place it in register with any one of said discharge openings, and a charging device for the presses which is movable with 105 said discharge spout, and is also movable relative to said discharge spout for carrying material therefrom to the presses.

9. The combination of a cooker, a plurality of presses arranged in relatively fixed 110 positions around said cooker, a charging device for the presses which is arranged to receive material from said cooker and is movable to place it in operative relation to one after another of said presses, and hydraulic actuating mechanism for moving 115 said charging device to carry the material from the cooker to the presses.

10. The combination of a cooker, a plurality of presses arranged in relatively fixed 120 positions around said cooker, a charging device for the presses which is arranged to receive material from said cooker and is movable to place it in operative relation to one after another of said presses, and fluid-pressure-operated mechanism for moving 125 said charging device to carry the material from the cooker to the presses, said actuating mechanism including fluid connections which permit movement of said mechanism 130

with said charging device from press to press.

11. The combination of a cooker, a plurality of presses arranged in relatively fixed 5 positions around said cooker, a charging device for the presses which is arranged to receive material from said cooker and is movable to place it in operative relation to one after another of said presses and fluid- 10 pressure operated mechanism for moving said charging device to carry the material from the cooker to the presses, comprising a cylinder, a piston movable therein and connected to said charging device, and fluid 15 connections for said cylinder including a swivel joint which permits movement of said cylinder with said charging device from press to press. 70

12. The combination of a cooker, a plurality of presses arranged in relatively fixed 20 positions around said cooker, a charging device for the presses which is arranged to receive material from said cooker and is movable to place it in operative relation to one after another of said presses, and fluid- 25 pressure operated mechanism for moving said charging device to carry the material from the cooker to the presses, comprising a cylinder, a piston movable therein and connected to said charging device, and fluid 30 supply and return connections for said cylinder including a common swivel joint which permits movement of said cylinder with said charging device from press to press. 80

13. The combination of a cooker, a plurality of presses arranged around said cooker, a charging device for the presses which is arranged to receive material from said cooker, a supporting frame for said 40 charging device mounted to swing about an axis concentric with said presses, and a rectilinear guide on said frame on which said charging device is adapted to reciprocate for carrying the material from the cooker 45 to the presses. 85

14. The combination of a cooker having a plurality of bottom discharge openings, a plurality of presses arranged around said cooker adjacent to said discharge openings, 50 a frame provided with a discharge spout and mounted to swing about an axis concentric with said discharge openings to place said spout in register with one after another of said openings, and a charging device for the presses which is movably 55 mounted on said frame to carry the material from said spout to the presses. 90

15. The combination of a press box having an open end, a ram movable in said box 60 for pressing the material, a pressure block

at the open end of the press box, a cylinder piston and piston rod for forcing said pressure block toward the press box, and an abutment which is constructed to embrace 65 said piston rod between said pressure block and said abutment for holding said pressure block rigid against movement in the opposite direction and which is movable away from the holding position, said cylinder and piston being adapted for operation to relieve 70 said abutment from the pressure of said pressure block. 75

16. The combination of a cooker, a plurality of presses arranged in relatively fixed 75 positions around said cooker, a charging device for the presses which is mounted to move beneath the cooker from an operative position relative to one of said presses to an operative position relative to another of said presses, said charging device being normally located substantially wholly underneath the cooker and being movable from a receiving position under the cooker outwardly for carrying a charge of material 80 from the cooker to a press. 85

17. The combination of a cooker, a plurality of presses arranged in relatively fixed 90 positions around said cooker, a charging device for the presses which is mounted beneath the cooker to swing about an axis substantially concentric with the cooker from an operative position relative to one of said presses to an operative position relative to another of said presses, said charging device being also movable from a receiving position outwardly for carrying a charge of material 95 from the cooker to a press, and the outermost portion of the charging device when in said receiving position lying substantially underneath the cooker. 100

18. The combination of a cooker, a plurality of presses arranged in relatively fixed 105 positions around said cooker, a charging device for the presses which is suspended from the bottom of the cooker and is arranged to move under the cooker from an operative position relative to one of said presses to an operative position relative to another of said presses, and is also movable from a position in which it receives a charge 110 of material from the cooker toward a press for carrying a charge of material to the press. 110

Witness my hand, this 15 day of July, 1914.
